UNITED STATES PATENT OFFICE

94,042

DESIGN FOR A PORTABLE REFRESHMENT BOOTH

Clifton E. Mowrer, Bethlehem, Pa.

Application October 19, 1934, Serial No. 53,697

Term of patent 7 years

To all whom it may concern:

Be it known that I, Clifton E. Mowrer, a citizen of the United States, and a resident of Bethlehem, in the county of Northampton and State of Pennsylvania, have invented a new, original, and ornamental Design for Portable Refreshment Booth, of which the following is a specification, reference being had to the accompanying drawing, forming part thereof.

I claim:

The ornamental design for a portable refreshment booth as shown.

CLIFTON E. MOWRER.
